ENGINE STARTING MECHANISM

Howard Baer, Jersey City, N. J., assignor to
 Eclipse Aviation Corporation, East Orange,
 N. J., a corporation of New Jersey

Application April 1, 1937, Serial No. 134,409

13 Claims. (Cl. 121—37)

This invention relates to starting devices for internal combustion engines.

One of the objects of the invention is to provide an engine starter of the torque applying type embodying novel means for producing engagement with and transmission of torque to a member of the engine to be started.

A further object of the invention is to provide in a starting device of the foregoing character, novel means for converting an axially directed pressure into a rotation producing force whereby the axial movement of the driving member is translated to the engine cranking member.

A further object of the invention is to provide a novel starting mechanism of the type employing a plurality of power actuated pistons one of which operates to produce engagement between the starting mechanism and a member of the engine to be started, and the other of which operates to impart a cranking torque to the engine engaging member.

Another object of the invention is to provide a multiple power member starter of the foregoing character which makes it possible, by the use of a novel construction, to obtain a quicker and more certain inter-engagement between the teeth of the engine engaging member and the engaged member of the engine, prior to any appreciable axial movement of the larger of the two power actuated pistons above referred to.

Other objects and advantages to be derived from the use of the invention reside in the specific construction, combination and interrelation of parts whereby a compact, efficient and easily operated and maintained unit is produced, all of which objects and advantages will appear more clearly upon an inspection of the following specification, with reference to the accompanying drawing illustrating the preferred embodiment of the invention. It is to be expressly understood however, that the said drawing is for the purpose of illustration only and is not to be construed as a definition of the limits of the invention, reference being had to the appended claims for this purpose.

In the drawing, wherein like reference characters refer to like parts throughout the several views:—

50 Fig. 1 is a longitudinal axial section through a device embodying the invention;

Fig. 2 is a slightly enlarged perspective view of the valve member;

Fig. 3 is an enlarged transverse sectional view 55 taken along line 3—3 of Fig. 1;

Fig. 4 is another enlarged transverse sectional view taken along line 4—4 of Fig. 1; and

Fig. 5 is an enlarged transverse view showing the relationship existing between two of the members at the time of valve closing. 5

With reference to the drawing, and more particularly to Fig. 1, the piston actuated unit is contained within a sectional housing including cylindrical parts 17 and 10, the latter having a flange 12 by which it is secured to the engine 10 crankcase 13 as by bolts 14, the flange being conveniently of a size standardized for aircraft engine starters. The engine crankshaft, or other drive shaft (not shown) is provided with a clutch element 11 engageable by the piston actuated 15 clutch element 15 as will be later more fully described.

Cylinder 17 has a head end 18 and a crank end 20, the latter being shown as an integral part of an internally splined tube 21. Slidably fitted 20 within the cylinder 17 is a piston 23 movable with a hollow screw 24 which is externally splined as at 25, to cooperate with the internally splined tube 21. Between the cooperating grooves 25 and 26 are placed a series of friction reducing 25 members shown as balls 27 assembled in a cylindrical cage 30, suitable stops 28 and 28a being provided at each end of the splined grooves to hold the cage 30 against more than predetermined endwise movement. A second screw 22 30 is drivably connected with the screw 24 by helical grooves or threads 29 and 31 which permit the axial travel of the piston 23 but cause rotation of the screw 22 because of friction reducing balls 36 assembled in cage 35 and inserted in the 35 helical grooves 29 and 31, stops 28a and 28b likewise serving to limit the endwise movement of the cage. An anti-friction thrust bearing 32 is preferably interposed between a flanged skirt 34 on the rear end of a spacer member 34b and 40 an inwardly extending circular portion 33 of the body 10, the said bearing 32 acting to take the axial thrust to which the inwardly extending rim 34a, on the forward end of the spacer member, is subjected when engaged by the forwardly 45 moving flange of head member 19. A spring 37 has one end resting against the closure plate 20 of the cylinder 17, and its opposite end abuts the thrust ring 38, which is, in effect, the outer race 38 of a ball-bearing assembly 40 axially movable 50 with but rotatably free of the piston 23, the intervening bearing balls 40 facilitating free rotation of outer race 38 of the bearing, the outer race being possibly constrained to rotation by the natural twisting tendency of a spring such as 55

the spring 37, as the latter is compressed in the forward travel of the piston. Piston rings 39 insure against the loss of pressure as the piston moves forward, and also yieldably oppose rotation of the piston, even though twisting of spring 37 should occasionally cause outer race 38 to rotate to some extent.

Due to the bolted split clamp connection 41 between the cylinder 17 and the body flange 16, the former may be quickly detached for removing any fouling that may occur where combustible cartridges are used as the source of fluid pressure to move the piston 23.

The present invention, as above indicated, includes improved means for automatically controlling both the meshing of parts 15 and 11, and the exhaust of the fluid pressure from the cylinder upon completion of the cranking operation. This combined meshing and exhaust control may be effected by providing a path along which the pressure fluid may flow to act directly and immediately upon the head portion 19 of the sleeve 22 whereby said sleeve 22 may move axially forward prior to and independently of the beginning of axial movement of the main piston 23 as is explained more fully here-in-after—the said head portion 19 of the sleeve 22 thus constituting, in effect, a separate piston with exposed surface area greater than the initial exposed surface areas of the piston 23 and parts integrated therewith—the annular boss 91 of the cylinder head serving to "block off" the major portion of the piston area with the parts in the relative positions shown in the drawing. Forward movement of piston 19 tends to compress the spring 47, to transmit, by way of said spring, a forward meshing movement to the clutch member 15, thereby bringing the latter into operative engagement with the engine member 11. As shown, the pressure fluid path leading to the piston 19 includes openings formed by cutting away the flanged forward end 70 of the exhaust valve 42 to form fingers 70 as indicated best in Fig. 2, whereby the fluid entering through chamber 56 may instantly pass directly into a long annular chamber between the rod 46 and the tube 71, which constitutes a centrally disposed extension of the piston 23, to which piston the flanged rear end of the tube 71 is connected by suitable screws 72 or equivalent means, as illustrated; the forward end of the annular chamber thus formed having communication with the bore of the sleeve 22 by virtue of recesses 52a formed in the nut 52 inserted on the forward end of the rod 46 and best viewed in Fig. 4, and also by virtue of the passage-way through the thickened forward portion 74 of the tube 71. This forward portion 74 is provided with sealing rings 76 which prevent seepage of fluid or particles contained therein backwardly into the space surrounding the tube 71, while at the same time facilitating and permitting free sliding movement of the tube within the bore of sleeve 22 as the piston 23 moves forward in the cylinder 17. The valve 42 is carried by the rod 46 and is of such a length that with the parts in the positions indicated in Fig. 1, a spring 49 will bear against the nut 52 on the rod 46 to hold said valve 42 on the seat formed in the head 44. At the commencement of an operative cycle of the motor, such as is occasioned by the delivery of fluid pressure to the chamber 56, this fluid pressure will assist the spring 49 in maintaining the exhaust valve 42 closed; but as the piston nearly reaches the end of its movement, a collar 53 extending inwardly of piston 23 will be brought into engagement with

the nut 52, as best shown in Fig. 5, and will be effective to unseat the exhaust valve 42. In this connection it will be noted (see particularly Figs. 3 and 5) that the central opening in collar 53 is so formed at 53a as to provide a plurality of inwardly extending projections or fingers 81 for abutment with the radial projections or outermost parts 82 of the nut 52 as indicated in Fig. 5, as the piston 23 approaches the end of its stroke, while at the same time this construction permits constant clearance between the said collar 53 and the rod 46 (as shown clearly in both Figs. 1 and 3) whereby the pressure fluid is always free to pass between the chamber 56 and the bore of sleeve 22—passage being first from chamber 56 to the bore 22 (at the beginning of the cycle of operations) and subsequently in the reverse direction to allow the pressure fluid to be exhausted in response to the opening of the exhaust valve 42—that is, its removal from its seat in the housing 44—by the engagement of the collar 53 with the nut 52 at the end of the stroke of the piston 23 as above described. The exhaust valve having been thus unseated, the spring 48 will be effective for holding it in open position, 15 its maximum opening movement being limited by a longitudinally slotted cylindrical stop 54 having a flange 66 abutting the end-surfaces of the fingers 67, formed by longitudinally slotting the neck portion 56 of the head end 18. This neck 30 56 is externally threaded, as shown at 68, to receive the housing 44, the latter being screwed upon the threads 68 until surface 69 of the housing 44 abuts the flange 66 of the stop 54 and with the inlet passage aligned with the longitudinal 35 slots 67a between fingers 67. Stop 54 is adapted to be first slipped over the valve-head 42; and due to the eccentricity of the apertured portion of the said stop, the said aperture has sufficient surface remaining to constitute a stop or abutment 54a for valve head 42 in the open position of the latter, while at the same time being apertured sufficiently to permit insertion and withdrawal over said valve head.

The piston having completed its operative 45 stroke, and the exhaust valve having been opened, the piston will be urged on its return stroke by the coil spring 37. During this return movement, the exhaust valve being held open, the cylinder will be effectively scavenged. Due to the action of the spring 48 the valve will remain open until such time as the piston collar 53 is brought to bear against, the fingers 70 at the end of valve stem 42 for again seating the valve, as shown in Fig. 3. This insures closing movement of the valve at 50 the time the piston has substantially completed its return movement, the closing being initiated and assisted by the action of the spring means 49 above described. It is thus apparent that the 55 exhaust means is of such construction as to remain open during the major portion of the return stroke of the piston so as to insure substantially complete scavenging. In order to permit the movement of the sleeve 22—for the purpose of meshing the parts 15 and 11 independently of the movement of the piston 23—without at the same time creating too severe an axial thrust on the driving sleeve 24 with which the said sleeve 22 is threadedly engaged, the ball-cage assembly 35 is preferably of a length somewhat less than the distance between retainer rings 28b and 28a whereby forward movement of the sleeve 22 to the extent necessary to induce complete mesh between parts 15 and 11 occurs prior to taking up of the thread-clearance between the end-balls 36 60 65 70 75

on the one hand, and the retainer-rings 28b and 28a on the other.

If during this meshing movement a collision should occur between the corners of the teeth 15 and 11 thus temporarily interfering with full engagement thereof the piston 19 and sleeve 22 will nevertheless continue to move axially forward in response to the urge of the pressure fluid which has entered its bore by 10 way of the communicating passage-ways above described, such continued forward movement of the piston 19 being possible because of the clearance between the forward end of the said piston and the jaw 15 to which the forward end is 15 splined as indicated at 88, the spring 47 also being sufficiently compressible to permit such relative axial movement. During this relative axial movement a certain amount of rotary movement reverse to the rotary movement of the 20 cranking will also occur due to the effect of the stationary threads of the outer sleeve 24 upon those of the sleeve 22 and such rotary movement will therefore relieve the condition of cornered tooth contact, whereupon spring 47 will expand 25 from its compressed condition and thereby press the jaw member 15 into full engagement with the engine member 11.

What is claimed is:-

1. In an engine starter the combination with a piston adapted for axial advance, helical means associated with the piston to produce rotary motion from said advance, an engine engaging member rotatable by said rotary motion, and means for moving said engine engaging member longitudinally but independently of said piston, said last named means and said piston being disposed so that the actuating fluid first acts upon said moving means and exerts engagement maintaining pressure thereupon during the entire axial advance of the piston, there being only a portion of the normal operating surface of the piston exposed to said actuating fluid at the beginning of the engine engaging operation.
2. In an engine starter the combination, with a housing, of a piston adapted for axial advance within said housing, helical means associated with the piston to produce rotary motion from said advance, an engine engaging member rotatable by said rotary motion, and means for moving said engine engaging member longitudinally but independently of said piston, said last named means and said piston being disposed so that the actuating fluid first acts upon said moving means and exerts engagement maintaining pressure thereupon during the entire axial advance of the piston, there being only a portion of the normal operating surface of the piston exposed to said actuating fluid at the beginning of the engine engaging operation, and means integral with said piston housing for initially closing off the remaining portion of the normal operating surface of said piston from the path of the actuating fluid which is acting upon said moving means to move the engine engaging member longitudinally independently of movement of said piston.
3. In an engine starter the combination with a piston adapted for axial advance, helical means associated with the piston to produce rotary motion from said advance, an engine engaging member rotatable by said rotary motion, and means for moving said engine engaging member longitudinally but independently of said piston, said last named means and said piston being disposed so that the actuating fluid first acts upon said moving means, there being only a portion of the normal operating surface of the piston exposed to said actuating fluid at the beginning of the engine engaging operation, said moving means including a second piston located between said first named piston and said engine engaging member and further acting as a part of the driving connection for translating the axial movement of said first named piston into a rotary cranking movement of said engine engaging member.
4. In an engine starter the combination with a piston adapted for axial advance, a housing therefor, helical means associated with the piston to produce rotary motion from said advance, an engine engaging member rotatable by said rotary motion, means for moving said engine engaging member longitudinally but independently of said piston, said last named means and said piston being disposed so that the actuating fluid first acts upon said moving means and exerts engagement maintaining pressure thereupon during the entire axial advance of the piston, and means integral with said housing for confining the actuating fluid to contact with a portion only of the normal operating surface of said piston, at the beginning of the engine engaging operation.
5. In an engine starter the combination with a piston adapted for axial advance, a housing therefor, helical means associated with the piston to produce rotary motion from said advance, an engine engaging member rotatable by said rotary motion, means including a second piston for moving said engine engaging member longitudinally but independently of said piston, said two pistons being disposed so that the actuating fluid first acts upon said moving means, and means integral with said housing for confining the actuating fluid to contact with a portion only of the normal operating surface of said first-named piston, at the beginning of the engine engaging operation, said portion having an effective pressure area less than that of said second piston.
6. In an engine starter the combination with a piston adapted for axial advance, a housing therefor, helical means associated with the piston to produce rotary motion from said advance, an engine engaging member rotatable by said rotary motion, means for moving said engine engaging member longitudinally but independently of said piston, said last named means and said piston being disposed so that the actuating fluid first acts upon said moving means, said moving means including a second piston located between said first named piston and said engine engaging member and further acting as a part of the driving connection for translating the axial movement of said first named piston into a rotary cranking movement of said engine engaging member, and means integral with said housing for confining the actuating fluid to contact with a portion only of the normal operating surface of said first-named piston, at the beginning of the engine engaging operation, said portion having an effective pressure area less than that of said second piston.
7. The combination with a rotatable engine engaging member and a non-rotatable driving member, of a piston for moving said driving member forward, a housing for said piston through which fluid enters to drive said piston and driving member forward, a valve controlling exhaust of the fluid, and means on said piston for actuating said valve, said means including a part apertured to permit the actuating fluid to

- act upon said engine engaging member prior to contact with the major part of the piston's working surface.
8. The combination with a rotatable engine 5 engaging member and a non-rotatable driving member, of a piston for moving said driving member forward, a housing for said piston through which fluid enters to drive said piston and driving member forward, and means including a second piston for driving said engine 10 engaging member forward, said last-named means also including a part carried by said first-named piston for directing the fluid that first enters the housing into contact with said second piston prior to contact of any of the fluid with the major 15 working surface of said first-named piston.
9. The combination with a rotatable engine 20 engaging member and a non-rotatable driving member, of a piston for moving said driving member forward, a housing for said piston through which fluid enters to drive said piston and driving member forward, means including a second piston for driving said engine engaging member forward, said last-named means also including a part carried by said first-named piston for directing the fluid that first enters the 25 housing into contact with said second piston prior to contact of any of the fluid with the major working surface of said first-named piston, and means including a member rotatably surrounding 30 said piston-carried part for translating the forward movement of said driving member into a rotary movement of said second piston and engine 35 engaging member.
10. The combination with a rotatable engine 40 engaging member and a non-rotatable driving member, of a forwardly moving piston for moving said driving member forward, a housing for said piston through which fluid enters to drive said piston and driving member forward, and means including a second forwardly moving piston having 45 telescopic engagement with said engine engaging member for driving said engine engaging member forward, said last-named means also including a yieldable thrust-transmitting connection between said second piston and said engine engaging member.
11. The combination with a rotatable engine 5 member and a non-rotatable driving member, of a piston for moving said driving member forward, a housing for said piston through which fluid enters to drive said piston and driving member forward, and means including a second piston having telescopic engagement with said engine engaging member for driving said engine 10 engaging member forward, said last-named means also including a part carried by said first-named piston for directing the fluid that first enters the 15 housing into contact with said second piston prior to contact of any of the fluid with the major 20 working surface of said first-named piston.
12. The combination with a rotatable engine 25 engaging member and a non-rotatable driving member, of a piston for moving said driving member forward, a housing for said piston through which fluid enters to drive said piston and driving member forward, means including a second piston having telescopic engagement with said engine 30 engaging member for driving said engine engaging member forward, said last-named means also including a part carried by said first-named piston for directing the fluid that first enters the 35 housing into contact with said second piston prior to contact of any of the fluid with the major 40 working surface of said first-named piston, and means including a member rotatably surrounding said piston-carried part for translating the forward movement of said driving member into a rotary movement of said second piston and engine 45 engaging member.
13. The combination with a rotatable engine 45 engaging member and a non-rotatable driving member, of a forwardly moving piston for moving said driving member forward, a housing for said piston through which fluid enters to drive said piston and driving member forward, and means including a second forwardly moving piston having 50 telescopic engagement with said engine engaging member for driving said engine engaging member forward, said last-named means also including a yieldable thrust-transmitting connection between said second piston and said engine engaging member.

HOWARD BAER.
